BUSHING INSULATOR

Harold L. Rorden, Barberton, Ohio, assignor to
 The Ohio Brass Company, Mansfield, Ohio, a
 corporation of New Jersey

Application February 4, 1938, Serial No. 188,691

7 Claims. (Cl. 174—12)

This invention relates to bushing insulators and more particularly to oil filled bushings made of porcelain or like material.

One object of the invention is to provide a bushing adapted to be filled with oil or other insulating liquid in which the liability of contamination of the insulating liquid by contact with the outer atmosphere is reduced to a minimum.

10 A further object of the invention is to provide a bushing insulator in which the danger of overstressing the insulating liquid is also reduced to a minimum.

15 A further object of the invention is to provide a bushing insulator having a plurality of baffles with means for improving the voltage gradient in the insulation.

20 A further object of the invention is to provide a device of the class named which shall be of improved construction and operation.

Other objects and advantages will appear from the following description.

The invention is exemplified by the combination and arrangement of parts shown in the accompanying drawings and described in the following specification and it is more particularly pointed in the appended claims.

In the drawings:

Fig. 1 is an elevation of a bushing insulator 30 with parts in section showing one embodiment of the present invention.

Figs. 2 and 3 are fragmentary sections showing modifications of the invention.

Fig. 4 is a view similar to Fig. 1 showing another form of the invention.

Figs. 5, 6, 7 and 8 are fragmentary sections of bushing insulators showing their modified features of the invention.

In the form of the invention shown in Fig. 1 the number 10 designates a hollow conductor 40 extending through a flange 11 arranged to be connected to an opening in a housing for electrical apparatus such as a switch housing or a housing for a transformer. At the lower end of the conductor 10 is a fitting 12 secured to the conductor and supporting the lower dome 13 of the bushing insulator. The dome 13 is preferably made of porcelain but may be made of other suitable insulating material. A shoulder 14 extends 45 outwardly from the upper portion of the dome 13 and supports the flange 11. The cone 15 rests on the flange 11 and carries an expansion chamber 16. Within the expansion chamber 16 is a compression spring 17 which supports a ring 50 18 which engages a collar 19 secured to the upper

end of the conductor 10. The spring 17 exerts a tension on the conductor 10 and a compression on the dome 13, cone 15 and flange 11, thus holding the parts of the insulator together. Secured to the lower end of the conductor 10 is a fitting 5 20 which carries a porcelain baffle tube 21 surrounding the conductor 10. A second porcelain baffle 22 is secured to the baffle 21 by cement joints 23 and 24. The dome 13 is provided with an extension 25 which projects through the flange 10 11 so as to increase the insulation between the conductor 10 and the flange. The space within the bushing not otherwise occupied is preferably filled with insulating oil or other dielectric liquid and the inner space 26 immediately surrounding 15 the conductor 10 is preferably separated from the remainder of the space within the bushing by the baffle 21 and a metal tube 27 which is secured to the upper end of the baffle 21 by a liquid tight joint at 28. The inner face of the tube 21 is 20 preferably coated with conducting material 29. This coating may be made of copper or other suitable metal sprayed upon the inner surface of the tube. There are several well known methods for coating porcelain with metal any one of which 25 may be used for this purpose. A passage 30 extends through the fitting 20 to connect the space 26 with the remainder of the space within the bushing. The gasket 31 is interposed between the expansion chamber 16 and the cone 15 to 30 form a liquid tight joint at this point and the inner edge of the gasket bears against the tube 27 with sufficient force to prevent circulation of the oil from the expansion chamber to the outer space within the bushing. Sufficient slippage is 35 permitted, however, to prevent stress due to differential expansion of the bushing parts. When the bushing and the expansion chamber are filled with oil, the oil will expand and contract due to temperature changes, producing a 40 breathing action through the upper portion of the expansion chamber. This will permit the oil in the expansion chamber to contact with the air which is breathed into the chamber and some of the moisture or other contamination in the air 45 may be absorbed by the oil in the expansion chamber. This oil, however, is not in direct contact with the main body of the oil in the bushing, but is separated from the main body by the tube 27 and the baffle 21. The space immediately surrounding the conductor 10 is of sufficient volume that the contaminated oil in the expansion chamber will never be drawn through the passage 30 into the space outside the baffle 21. Deterioration of the oil in the space 26 is 50 55

of no serious consequence because this space is preferably shunted by a jumper 32 so that even if the oil in the space 26 is not a perfect dielectric, there will be no breakdown of the oil in this region because it is not subjected to electric voltage. It has been found advantageous to provide a shunt across this space to prevent overstress of the oil even when the oil is not contaminated, because, where the space 26 is not shunted, it is subject to a very high voltage due to the fact that electrostatic lines of force are concentrated in this zone adjacent the conductor, and also due to the fact that oil has a lower specific inductive capacity than porcelain and consequently, there is a greater drop of potential through the oil than there would be through a like thickness of porcelain. The coating 29 and jumper 32, therefore, perform a double function of short-circuiting the zone of highest electrical stress and the zone most apt to contain oil which has been affected by contact with the outer atmosphere.

By extending the dome 13 through the flange 11, additional insulation is provided between the conductor and the flange to compensate for the shunted space 26 about the conductor. This insulation is more advantageously placed than the oil in the space 29 because of the greater area at the greater distance from the axis of the conductor. By this arrangement the voltage stress is allocated in the portion of the insulator farther removed from the axis and in a zone where the lines of force are less concentrated so that the dielectric is more effective in withstanding the voltage.

In order to reduce the danger of corona or arcing from the flange toward the expansion chamber, a pocket 33 is provided in the lower portion of the cone 15 and the inner surface of the pocket is metallized and connected with the flange so that the electrostatic lines of force will emanate from the lining of the pocket directly into the porcelain and not into the atmosphere.

The form of the invention shown in Fig. 2 is similar to that in Fig. 1 except that the baffles 21 and 22 are both metallized on both their inner and outer faces, there being sufficient space at the ends of the baffles which is not coated to prevent discharge about the ends of the baffles. The adjacent coatings are connected by jumpers 34 and 35, thus shunting the oil space between the baffles and placing the entire voltage stress upon the porcelain. The conductor plates thus provided between the porcelain baffles forms a condenser arrangement which assists in producing a better voltage gradient between the conductor 10 and the flange 11.

In the form of the invention shown in Fig. 3 the upper portion of the outer surface of the dome 13 is metallized as shown at 36, the lower edge of the metal coating terminating in a pocket 37 forming a flux control for preventing electrostatic discharge at the lower edge of the coating 36. The flux control 37 is preferably located far enough down on the dome 13 so that it will be always submerged in the insulating fluid in the housing for the electrical apparatus served by the bushing. This prevents any danger of discharge downwardly from the flange 11.

In the form of invention shown in Fig. 4 the dome 13 terminates at the flange 11 and an additional keg 38 is carried by the flange within the outer shell of the bushing to help withstand the voltage between the conductor and the flange. In this form of the invention, instead of utilizing

the inner porcelain baffle 21 to divide the oil space within the bushing, a special metal tube 39 surrounds the conductor 10 and is flared outwardly at its upper end to form a flange 40 which is caught between the upper end of the cone 15 and the expansion chamber 16 forming a tight joint at this point. A small tube 41 extends through the wall of the tube 39 and projects upwardly inside of the conductor 10 to a point where it communicates with the outer atmosphere. This permits escape of air from the space within the bushing surrounding the tube 39 as oil is filled into the bushing. The oil will flow down in the space 26 between the conductor and the tube 39 and enter the outer portion of the bushing through the passage 30 forcing the air out through the tube 41. The space 26 between the conductor 10 and the tube 39 is sufficient to accommodate the ebb and flow of the oil due to any breathing action so that contamination due to contact with the outer atmosphere will not affect the oil outside of the tube 39.

Fig. 5 shows a different arrangement for permitting escape of air from the outer portion of the bushing when the bushing is being filled with oil. In place of the tube 41 a valve 42 permits escape of air from the outer portion of the bushing but prevents entrance of oil into the bushing directly from the expansion chamber.

In the form of invention shown in Fig. 6 a metal tube 43 is soldered to the metal coating 29 on the baffle 21 and has its upper end turned outwardly and caught beneath the expansion chamber 16 as shown at 44. A tube 45 similar to the tube 41 in Fig. 4 connects the space outside of the baffle 21 with the outer atmosphere to permit escape of air when the bushing is filled with oil.

In the form of invention shown in Fig. 7 a tube 46 is soldered to the baffle 21 and extends past a gasket 31 as in Fig. 1. In this case the space within the expansion chamber communicates with the upper end of the tube 46 through a passage 47 which is elevated somewhat above the bottom of the expansion chamber providing a sump 48 for the accumulation of moisture which may be entrapped by the oil in the expansion chamber.

A similar trap 49 may be formed at the lower end of the tube 39 as shown in Fig. 8 by closing the lower end of the tube by means of packing 50 and providing an opening 51 for the escape of oil into the outer portion of the bushing at a point somewhat above the lower end of the tube 39.

I claim:

1. The combination with an electrode having an opening therethrough and a conductor extending through said opening, of a bushing insulator separating said conductor from said electrode, said bushing insulator comprising a housing having space therein closed at its bottom, electric insulation within said space including an insulating liquid, said space being divided into inner and outer compartments, the dominant insulation in said space between said electrode and conductor being disposed in said outer compartment, the liquid in said inner compartment having its surface exposed to atmospheric pressure, said compartments being sealed against communication with each other at their upper ends but connected at their lower ends and being constructed and arranged so that the dominant portion of all liquid entering said outer compartment to compensate for contraction of the liq-

uid in said outer compartment will be supplied from the inner compartment, said inner compartment having sufficient capacity between the surface of the liquid therein and the point of communication between said compartments to accommodate the ebb and flow of the insulating liquid due to expansion and contraction of the liquid in said outer compartment without passage from said inner to said outer compartment 10 of liquid which has been contaminated by contact with the atmosphere.

2. In combination a bushing insulator comprising a housing, an expansion chamber communicating with the outer atmosphere and connected with said housing, a conductor extending through said housing and having liquid tight connection with said housing at the lower end of said housing and a baffle tube surrounding said conductor and communicating at its upper 20 end with said expansion chamber and at its lower end with the interior of said housing outside of said baffle tube and dividing the interior of said housing into inner and outer compartments, said baffle tube at its upper end forming a liquid 25 tight partition between the upper portions of said compartments and preventing direct passage of said insulating liquid from said expansion chamber to said outer compartment, the inner and outer walls of said outer compartment being insulated from each other so that insulating liquid in said outer compartment forms an effective portion of the bushing insulation.

3. In a bushing insulator, a dielectric housing, a conductor extending through said housing, the space within said housing being closed against escape of liquid through the bottom of said housing, an expansion chamber at one end of said housing, and a tube surrounding said conductor and communicating at one end with said expansion chamber and at the other end with the space within said housing outside of said tube for preventing direct passage of insulating liquid from said expansion chamber to the space within said housing outside of said tube, said space having outer and inner walls insulated from each other.

4. In a bushing insulator, a dielectric housing, a conductor extending through said housing, the space within said housing being closed against escape of liquid through the bottom of said housing, an expansion chamber at one end of said housing and communicating with the outer atmosphere, a tube surrounding said conductor and communicating with said expansion chamber and separating the space immediately adjacent said conductor from the space outside of said tube and means separating said outside space from said expansion chamber to prevent oil from passing directly from said expansion chamber to said 60 outside space, said tube communicating with said outside space at the end thereof opposite said expansion chamber, the inner surface of said tube being conducting and being electrically connected with said conductor to shunt the space 65 between said tube and conductor, said outside

space having inner and outer walls insulated from each other.

5. In a bushing insulator a dielectric housing, a conductor extending through said housing, the space within said housing being closed against escape of liquid through the bottom of said housing, a dielectric baffle tube surrounding said conductor, a conductive coating on the inner surface of said baffle tube, an expansion chamber on said housing and communicating with the interior 10 of said baffle tube, means for preventing direct communication between said expansion chamber and the space within said housing outside of said baffle tube, said expansion chamber communicating with said outside space through the space 15 between said conductor and the wall of said baffle tube and means for electrically connecting said conductor with the conductor coating on the interior of said baffle tube to shunt the space between said conductor and the wall of said baffle 20 tube, said outside space having inner and outer walls insulated from each other.

6. In combination a bushing insulator comprising an insulator housing, a conductor extending through said housing, the space within said housing being closed against escape of liquid through the bottom of said housing, an expansion chamber disposed on top of said housing, a baffle tube surrounding said conductor and communicating at its upper end with said expansion chamber and at its lower end with the space within said housing outside of said tube, said baffle tube providing communication between said expansion chamber and the space within said insulator outside of said tube, said space 35 being otherwise completely sealed against passage of liquid to and from said expansion chamber, insulating liquid filling said insulator and extending into said expansion chamber, the space within said insulator outside of said tube having 40 inner and outer walls which are insulated from each other so that the insulating liquid within said space forms an effective part of the bushing insulation.

7. In combination a bushing insulator housing, a conductor extending through said housing, an expansion chamber at the upper end of said housing, a baffle tube surrounding said conductor and communicating at its upper end with said expansion chamber and at its lower end with the space within said housing outside of said tube, the space within said housing being closed against escape of liquid through the bottom of said housing, the point of communication between the upper end of said tube and said expansion chamber being located above the bottom of said expansion chamber and the wall of said tube having liquid tight connection with the bottom of said expansion chamber and forming a liquid tight seal between said expansion chamber and the upper end of the space within said housing outside of said tube to provide a water trap in the bottom portion of said expansion chamber separated from said outside space.

HAROLD L. RORDEN.
